UNITED STATES PATENT OFFICE.

JAMES F. McELROY, OF ALBANY, NEW YORK, ASSIGNOR TO THE CONSOLIDATED CAR HEATING COMPANY, OF SAME PLACE.

CAR-HEATING APPARATUS.

SPECIFICATION forming part of Letters Patent No. 471,312, dated March 22, 1892.

Application filed December 30, 1890. Serial No. 376,299. (No model.)

To all whom it may concern:

Be it known that I, JAMES F. McELROY, a citizen of the United States, residing at Albany, in the county of Albany and State of New York, have invented certain new and useful Improvements in Car-Heating Apparatus, of which the following is a specification, reference being had therein to the accompanying drawings.

- 10 This invention relates to new and useful improvements in car-heating apparatus; and it consists in the peculiar construction of the various parts of a hot-water heating apparatus of that kind in which the water of circulation is heated by the injection of steam, and specifically in the construction of an air-inlet in the steam-supply pipe controlled by a check-valve to prevent the withdrawal of the water of circulation into the steam-supply pipe in 15 the event of a vacuum being formed in such supply-pipe, and, further, in the peculiar construction, arrangement, and combination of the various parts, as more fully hereinafter described.
- 20 In the drawings, Figure 1 is a perspective view of a hot-water heating apparatus embodying my improvements. Fig. 2 is an enlarged detail section of the return-bend and check-valve. Fig. 3 is a detail vertical section 25 through the steam-heater.
- 30 A is the hot-water heating-stove.

B are the circulating-pipes within the car.

C is the expansion-drum.

D is the main steam-supply pipe or train-

35 pipe.

E is the branch supply-pipe entering the car.

F is the overflow-pipe connected with the expansion-drum and extending through the 40 car-floor.

G is a valve controlling the steam-supply, and H is a valve controlling the overflow-pipe.

I is an extension of the steam-supply pipe E, carrying said pipe above the water-level 45 in the drum C, connecting it into the return-bend J at the top. The pipe I' of the pipe I extends downward and connects into the top of the heater J', in which the steam is com-

mingled with the water and heats and circulates it. The steam passes out through a hose-nozzle into a surrounding body of gravel, as

shown in Fig. 3, the water of circulation passing up through the bottom of the heater and out through the pipe J² to the expansion-drum.

K is a check-valve placed in the steam-supply pipe opening inward.

In the use of an apparatus of this kind it has been found that when the engineer shuts off steam at the locomotive, the pipes remaining connected, the condensation of the steam 60 in the train-pipe D causes a partial vacuum therein, and in the event of the check-valve K being defective this vacuum will draw the water from the water-circulating system into the train-pipe, where it is apt to freeze, and 65 thus interrupt the operation of the entire system. It is evident that as the pipe I E forms one arm of a siphon, of which the pipe I' is the other arm, and if the vacuum in the train-pipe is of sufficient force to carry the water 70 down to the train-pipe, a siphon will be formed which will empty the entire system. It therefore becomes important to provide against this contingency and prevent this siphoning out of the water. To this end I construct the 75 return-bend J with a side outlet L, into which is connected the pipe M, which connects at its lower end with the overflow-pipe F. In this pipe is placed a check-valve N, which is closed by the pressure of the steam within 80 the steam-supply pipe J; but in the event of the formation of the vacuum in that pipe the difference in pressure on the opposite sides of the check-valve will cause it to open inward and allow air to pass in from the overflow- 85 pipe, which at all times has a connection with the outside of the car. This is accomplished by so constructing the valve H that at all times there is a passage-way opening through it. It is evident that this connecting-pipe M 90 may terminate in the car or may pass to the outside of the car, if desired; but either of these forms is objectionable, for the reason that the check-valve N may become leaky and allow the escape of steam therefrom. By 95 connecting it into the overflow-pipe any loss of steam caused by defective valve N will be carried by the usual channel of escape for the overflow.

What I claim as my invention is—

1. In a hot-water heating apparatus adapted to be heated by the injection of steam therein,

the combination, with the circulating-pipes, expansion-drum, and overflow-pipe, of a steam-supply pipe entering said system, an air-inlet in the supply-pipe, and a check-valve in said 5 inlet closed by the direct pressure of the steam within said pipe and opened by atmospheric pressure passing through the overflow-pipe, substantially as described.

2. In a hot-water heating apparatus adapted 10 to be heated by the injection of steam therein, the combination, with the circulating-pipes, expansion-drum, and overflow-pipe, of a steam-supply pipe entering said system, a connection between said steam and overflow pipes, 15 and a check-valve in said connection, substantially as described.

3. In a hot-water heating apparatus, the combination of a system of circulating-pipes, an expansion-drum and an overflow-pipe, a steam-supply pipe entering said system and 20 discharging therein, a portion of said steam-supply extending above the water-level in said drum, and a connection between said extension and the overflow-pipe, substantially as described.

25 In testimony whereof I affix my signature in presence of two witnesses.

JAMES F. McELROY.
